UNITED STATES PATENT OFFICE.

JAMES E. DANN, OF BROOKLYN, NEW YORK, ASSIGNOR TO THE AMERICAN LAUNDRY MACHINERY COMPANY, OF NORWOOD, OHIO, A CORPORATION OF OHIO.

WASHER-TIMING DEVICE.

1,397,726.

Specification of Letters Patent. Patented Nov. 22, 1921.

Application filed January 25, 1917, Serial No. 144,426. Renewed January 28, 1921. Serial No. 440,804.

To all whom it may concern:

Be it known that I, JAMES E. DANN, citizen of the United States, residing at Brooklyn, in the county of Kings and State of New York, have invented certain new and useful Improvements in Washer-Timing Devices, of which the following is a specification.

This invention relates to washing machines and more particularly to timing devices therefor. The object of the invention is to provide improved mechanism, preferably operated by the washing machine, which after the lapse of a given period, determined by the operator, opens the drain valve, indicates visually and by an alarm that the operation is finished, informs the operator of the nature of the next operation to be performed, and may also stop the machine.

Further objects of the invention are in part obvious and in part will appear more in detail hereinafter.

The invention comprises the apparatus hereinafter described and claimed.

In the drawings, Figure 1 is a front elevation, partly broken out and in section, showing a portion of a washing machine with my invention applied thereto; Fig. 2 is a rear elevation, partly broken out, of the timing mechanism; Fig. 3 is a plan view thereof; Fig. 4 is a cross section, on a larger scale, on the line 4-4, Fig. 1; Fig. 5 is a similar section on the line 5-5, Fig. 1; Fig. 6 is a front elevation of a portion of the device, showing a modification; and Fig. 7 is a sectional elevation on the line 7-7, Fig. 6.

The invention may be applied to any form of washing machine, whether of the dolly, drum or other type, but for convenience has been shown applied to a drum machine, whose outer tub or casing is indicated at 1. Said casing is suitably mounted and is provided with a drain pipe or conduit 2 in which is a suitable quick opening drain valve 3. The drum 4 within said casing is connected to a shaft 5 driven in any suitable manner, as by power applied to the gear wheel 6 which may be rotated intermittently in opposite directions. Any member of the driving mechanism, for example the gear 6, may be provided with means, such as the roller 7, for actuating the timing device to be described, although said device may be operated from some other power source than the machine itself, if desired.

The timing device comprises a frame 10 having a bracket 11 fastened to a suitable support, such as the machine tub. In said frame is journaled a horizontal screw shaft 12 provided with a ratchet wheel 13 co-operating with an actuating gravity pawl 14 hinged to a collar 15 adjustable vertically on a sliding rod 16 having yielding connections at 17 to a rod 18 whose lower end is guided in a support 19 and is provided with a foot 20. The rod 16 drops by gravity to its lowest position, shown in Fig. 4, its downward movement being limited by a pin 16^a which engages a part of the support 11, but each time the gear 6 makes a revolution, in either direction, the roller 7 engages the foot 20 and lifts said rod, causing the pawl and ratchet devices to turn the screw shaft one notch. Said shaft is held in its new position by a spring holding dog 21.

At one side of the screw shaft, and parallel therewith, is a rod 22 which serves as a guide for a traveler 23 sliding on said rod and whose body portion has a smooth recess to receive the screw shaft, whereby said traveler is supported by both the shaft and rod 22 and can move longitudinally thereof. Said body is also provided with two holes for rods 24 attached to a nut segment 25 held by a spring 26 in coupled relation with the screw threads. The outer ends of said rods 24 are connected by a thumb piece 27, below which is a finger hold 28 on the body. By pressing in the thumb piece the traveler may be released from the screw shaft and adjusted to any position thereon and then again coupled therewith. Said traveler also is provided with an indicator such as the pointer 29, traveling over a scale 30 on the frame graduated in suitable divisions to indicate either the number of revolutions of the drum or elapsed time in minutes, preferably the latter. The traveler also is provided with a pawl arm 31, the purpose of which will hereafter appear.

At one end of the frame is located an upright tubular casing 32 in which is a compression spring 33 surrounding a rod 34 having a head 35 on its upper end and a latching collar 36 below the casing. Said collar has a square upper shoulder 37 for latching engagement with the latch 38, formed by the bent end of rod 22 which passes through an opening in the frame,

The lower portion of the collar is beveled or inclined at 39 to pass the latch 38 on the setting movement, during which it pushes the latch back and stretches the locking 5 spring 40. Rod 34 extends below the collar 36 and is provided with suitable connections, such as the chain 41, to the drain valve 3.

When the parts are set in the operative 10 condition, shown in Fig. 1, the head 35 is withdrawn into the casing 32, the drain valve is closed, and the latch 38 lies above the collar 36. Rotation of the screw shaft by the machine moves the traveler to the left 15 in Fig. 1, and as it approaches the limit of its travel it strikes a collar 42 attached to rod 22 and moves said rod to the left, thereby disengaging the latch 38 from collar 36, whereupon the rod 34 is forced up by the 20 spring 33 to open the drain valve and drain the machine. Rod 34 may also be connected by a cable 43 or other means to the switch or other device 44 for controlling the machine so as to cut off the power and stop 25 the machine, although this is not essential.

When rod 34 rises it projects the head 35 above the casing and indicates visually to the operator that the timing device has operated. By painting the head 35 one color, 30 say red, and the casing 32 another color, say black, the operator can tell at a glance which machine of a number has been drained.

Suitable means is also provided for 35 audibly indicating the conclusion of the operation. For this purpose the frame carries a bell or gong 45 having a clapper 46 on a spring metal lever 47 pivoted on the frame. Said clapper is normally held away from the gong by a light spring 48 but 40 when the collar 36 rises it strikes one arm of the lever 47 and throws the clapper down against the gong sounding the alarm.

The device also advises the operator of 45 the nature of the next operation to which the goods are to be subjected. This is particularly desirable when a given batch of articles are to be subjected to several successive treatments, for example, with a different kinds of solutions. Two different arrangements for this purpose are shown in the 50 drawings.

In Fig. 1 the frame is provided with an extension 49 having a sight opening 50 and provided with a hollow boss 51 forming a 55 journal for a shaft 52 having a head 53 for turning the same and a back plate 54 to whose front face is fastened a card 55 having a series of sets of indicia disposed circumferentially around the center and so arranged 60 as to be successively exposed through the sight opening. Each time the traveler approaches the end of the stroke the arm 31 thereon engages a tooth of a ratchet 56 on the back of plate 54 and turns said plate 65 and the indicating card to expose a new set

of indicia. Backward rotation is prevented by the dog 57. When the operator is advised that a machine has drained he can tell from inspection of the indicator what is the character of solution to be employed and also the period of the next operation and sets the machine accordingly. 70

Different kinds of goods frequently require differing series of operations, for example, white shirts would be subjected to a 75 different set of operations from colored goods, flat work, etc. This is taken care of in the apparatus just described by substituting a different indicia card, properly inscribed, for the one in the machine. 80

In the apparatus shown in Figs. 6 and 7 the indicator will take care of several different series without change. As shown the frame is provided with a cylindrical casing 58 having several hinged doors 59 covering separate sight openings. Within the casing is a skeleton drum 60 whose cylindrical surface bears several sets of indicia the items of which appear in turn before the several sight openings. Said drum has 90 a shaft 61 extending through the bottom of the casing and provided with a ratchet wheel 62 and notched wheel 63 which coöperate respectively with the operating pawl arm 31^a on the traveler and the holding dog 57^a. 95 By opening the proper one of the doors 59 the machine is ready for any desired sequence of operations. 100

What I claim is:

1. A washing machine having an operating member, and means actuated thereby for indicating to the operator the conclusion of the washing operation and the character of the next washing operation to be performed. 100
2. A washing machine having an operating member, and means actuated thereby for indicating to the operator at the conclusion of each washing operation the character of the next operation to be performed. 105
3. A washing machine having an operating member, and means actuated thereby for indicating to the operator at the conclusion of each washing operation the character of the next operation to be performed, said means being adjustable to indicate any one 110 of several different sets of washing operations. 115

4. A washing machine having an operating member, a normally concealed signal device visible at a distance from the machine 120 when exposed thereon, and means actuated by said member for exposing said device to view at the conclusion of the washing operation.

5. A washing machine having an operating member, a normally concealed signal device visible at a distance from the machine when exposed thereon, and means actuated by said member for exposing said device to view at the conclusion of the wash- 125 130

- ing operation and for simultaneously indicating to the operator the character of the next washing operation.
6. A washing machine attachment, comprising an inclosing casing, a signal device normally concealed therein and visible at a distance from the machine when exposed to view from the outside of said casing, and automatically operated means for so exposing said signal device at the conclusion of the washing operation.
7. A washing machine provided with an operating member and a drain valve, spring means for opening said valve, means for preventing operation of said spring means, and means actuated by said member and adapted at the conclusion of the washing operation to release said spring means for opening said valve and to indicate to the operator the conclusion of the operation.
8. A washing machine provided with an operating member and drain valve, and a second member operatively connected with said valve, said second member being actuated by said first member and adapted at the conclusion of the washing operation to open said valve and to indicate to the operator the conclusion of the operation.
9. A washing machine attachment, comprising a support, a movable member thereon, means tending to move said member in one direction, means for normally preventing said movement, means operated in timed relation with said washing machine for releasing said member for movement, a drain valve operated by said member, and a signal also actuated by said member.
10. A washing machine attachment, comprising a movably mounted member, means tending to move said member in one direction, means for preventing movement of said member, means operated in timed relation with said washing machine for releasing said member for movement, a drain valve operated by said member, and a signal device also operated by said member to indicate the conclusion of the washing operation.
11. A washing machine attachment, comprising a support, a movable member thereon, means tending to move said member in one direction, a latch for normally preventing such movement, latch actuating means operated in timed relation with the washing machine, a drain valve operated by said member, and a signal operated at the conclusion of the washing operation.
12. A washing machine provided with an operating member and a drain valve, a normally concealed signal device visible at a distance from the machine when exposed thereon, and means actuated by said operating member and adapted at the conclusion of the washing operation to open said valve and expose said signal device to indicate to the operator the conclusion of the washing operation.
13. A washing machine provided with an operating member and a drain valve, a normally concealed signal device visible at a distance from the machine when exposed thereon, means actuated by said operating member and adapted at the conclusion of the washing operation to open said valve and expose said signal device to indicate to the operator the conclusion of the washing operation, and means actuated simultaneously with said signal device for indicating to the operator the character of the next washing operation to be performed.
14. A washing machine attachment, comprising a support, a movable member thereon, means tending to move said member in one direction, a latch for normally preventing such movement, latch actuating means operated in timed relation with the washing machine, a drain valve operated by said member, and a normally concealed signal device operated by said member and adapted when exposed to indicate the conclusion of the washing operation.
15. A washing machine attachment, comprising a support, a movable member thereon, means tending to move said member in one direction, a latch for normally preventing such movement, latch actuating means operated in timed relation with the washing machine, a drain valve operated by said member, and an audible signal also actuated by said member.
16. A washing machine attachment, comprising a support, a movable member thereon, means tending to move said member in one direction, a latch for normally preventing such movement, latch actuating means operated in timed relation with the washing machine, a drain valve operated by said member, a normally concealed signal device operated by said member and adapted when exposed to indicate the conclusion of the washing operation, and an audible signal also actuated by said member.
17. A washing machine attachment, comprising a support, a movable member thereon, means tending to move said member in one direction, a latch for normally preventing such movement, latch actuating means operated in timed relation with the washing machine, a drain valve operated by said member, and means actuated by said latch actuating means for indicating to the operator the character of the next operation.
18. A washing machine attachment, comprising a suitable support, a reciprocating traveler thereon, means operated in timed relation with the washing machine for moving said traveler in one direction, means arranged as said traveler approaches the end of said movement to indicate the conclusion of the washing operation, and means for re-

leasing said traveler from its operating means whereby it may be freely moved manually in the opposite direction.

19. A washing machine attachment, comprising a suitable support, a reciprocable traveler thereon, a drain valve actuating member, a signal device, means operated in timed relation with the washing machine for advancing said traveler in one direction, 10 means whereby the advancing movement of said traveler produces operation of said signal device and drain valve operating member, and means for releasing said traveler from its operating means, whereby it can be 15 freely retracted from its advanced position.

20. A washing machine attachment, comprising a support, a movable traveler thereon, a movable operating member, means tending to move said member in one direction whereby to open the drain valve of the 20 washing machine, a latch normally preventing such movement, said latch being actuated by said traveler, and means having step by step movement actuated by said traveler for indicating at the conclusion of 25 each washing operation the character of the next washing operation to be performed.

In testimony whereof I affix my signature.

JAMES E. DANN.
